UNITED STATES PATENT OFFICE

AYRAULT D. FERGUSON, OF KANSAS CITY, KANSAS

POCKET FOUNTAIN TOOTHBRUSH

Application filed December 26, 1930. Serial No. 504,757.

This invention relates to fountain brushes and particularly brushes constructed for use as a tooth brush and has for its primary object the provision of a novel combination of 5 parts which form a tooth brush, within which may be carried the cleaning compound which is fed from the combined magazine-handle as needed.

One of the primary objects of the present 10 invention is the contemplation of a tooth brush structure, wherein is incorporated a brush-head and a magazine, between which is interposed a coupling formed to allow interchanging of a novel feeding means 15 which may be easily and quickly altered to convey cleaning compound of different character from magazine to brush-head.

One of the objects of the instant invention 20 is to provide a fountain tooth brush which may be entirely inclosed and carried in the pocket without danger of soiling the clothes.

A yet further object of the invention is 25 the contemplation of a fountain tooth brush, within which is built unique feeding mechanism which is cheap to manufacture, easy to assemble and is not likely to get out of order.

Minor objects of the invention and specific 30 details of construction will appear during the course of the detailed specification, referring to the accompanying drawing, wherein:

Figure 1 is a longitudinal central section 35 through a fountain tooth brush assembly made in accordance with this invention.

Fig. 2 is a side elevation of the same with the head-housing removed.

Fig. 3 is an enlarged detail fragmentary 40 section through a part of the brush assembly at the coupling member.

Fig. 4 is an enlarged vertical cross section 45 through the brush taken on line IV-IV of Fig. 1.

Fig. 5 is a similar section taken on line 50 V-V of Fig. 1.

Fig. 6 is a modified form of head-housing 55 for the brush, showing the same in section and in place.

Fig. 7 is a perspective sectional view 60 through the modified form of head-housing.

Fig. 8 is a fragmentary longitudinal section through a modified form of the brush, taken at the point of coupling, and

Fig. 9 is a view of the feeding screw as used 55 in the modified form of construction shown in Fig. 8.

Many methods of manufacturing the fountain tooth brush might be followed without departing from this invention and but two 60 forms are illustrated in the accompanying drawing.

Like reference characters refer to similar parts throughout the many views and the numeral 12 indicates a magazine which is formed to serve as a handle for the brush, and 65 which is hollow to receive a cleaning compound of any character. A brush head 14, provided with bristles 16 is constructed to be detachably connected to magazine 12 through the intermediacy of a coupling 18 which has 70 an opening 20 therethrough communicating with a way 22 formed within the brush head 14. Way 22 connects with lateral openings 24 which allow the escape of the cleaning compound to places within the bristles 16 75 where it may be utilized when the brush is brought into play. A screw-threaded neck 26, formed on the brush head 14, enters a tapped opening 28 in the end of coupling 18. The inner side of magazine 12 is screw- 80 threaded as at 30, which threads are engaged by coacting threads 32, formed on the outer side of the offset end of coupling 18. Such offset forms a shoulder 34 against which bears 85 the end of magazine 12 and another set of threads 36 receive the threaded end of head-housing 38 as illustrated in Fig. 1. This head-housing covers the brush head to protect the same when the appliance is not in use 90 and, as shown in Figs. 6 and 7, this part of the assembly may be made up in a form different than that shown in Fig. 1.

In the instance shown in Figs. 6 and 7, the head-housing is a flexible member 40, which 95 slides over the brush head 14 in the manner illustrated. This form of head-housing is somewhat different than the form shown in Fig. 1, but serves the purpose equally as well and may be utilized in the combination if desired. Figs. 1 to 5 inclusive show a construc- 100

tion especially adapted for feeding a cleaning compound of a pasty consistency. When the magazine 12 is to be filled, the brush head is unscrewed and a tube of paste positioned 5 in its stead, whereby the contents thereof may be forced into the magazine 12 below piston 42 which has previously been moved to a position close to the end of magazine 12 opposite head-housing 14. Assuming that magazine 10 12 is filled, and that the fountain brush is assembled ready for use, it remains now to describe the preferred embodiment of the feeding mechanism, which is adapted for use with cleaning paste.

15 The internal threads 30 formed within magazine 12 extend throughout the length thereof and piston 42 has threads on the annular periphery thereof which engage said threads 30. An oval-shaped opening 44, 20 formed centrally through piston 42, receives rod 46 which is likewise oval-shaped in cross section in order that the piston 42 may be driven when the rod is rotated and also to allow movement of piston 42 longitudinally 25 along said rod. To rotate this rod 46, a knurled cap 48 is provided which serves the two-fold purpose of closing one end of the magazine and acting as an operating member for rod 46. Cap 48 also centers rod 46 and, 30 with bearing plate 50, maintains the same in operative position. Bearing plate 50 is formed to provide a pair of diametrically opposite lugs 52, which extend into grooves 54 formed in the side of magazine 12. When 35 moving bearing plate 50 into the operative position, coupling 18 is removed from magazine 12 and the plate 50 moved into the position shown in Fig. 1. Coupling 18 holds bearing plate 50 in position and the lugs 52 preclude its rotation with rod 46, the reduced 40 end 55 of which enters opening 56 of plate 50.

To carry out one of the important features of the invention, this end of rod 46 is specially formed to present a squared length 58 45 which engages means for feeding powder to the brush head 14 as is hereinafter set down. When the structure is used as illustrated in Figs. 1 to 5, however, a bushing 60 is passed over the squared length 58 which is held in 50 place by a screw 62 in a manner clearly shown in Fig. 3. This construction presents an effective bearing for the end of rod 46 and perforations 64 through plate 50 allow the 55 passage of the cleaning compound to a brush head. The operation of this preferred form is extremely simple, in that merely turning a cap 48 causes rod 46 to rotate and carry piston 42 longitudinally within magazine 12 to force cleaning compound through perforations 64 and into way 22 through the 60 coupling 18.

It is oftentimes desirable to feed cleaning compound in powder form to the brush head of this article. To meet this requirement, 65 a slightly different form of coupling is used

as indicated at 80, Fig. 8. This coupling 80 holds plate 50 in position in exactly the same manner as did coupling 18, the main difference in character between the two being an enlarged opening 82 which houses the helical 70 screw 84. The squared length 58 of rod 46 enters the squared socket 86 formed in screw 84 and turns the same as rod 46 is rotated by the manipulation of cap 48. Obviously 75 the only act necessary to position this screw 84 is the removal of bushing 60 and screw 62. It is to be seen that the feeding means of this fountain brush is within the magazine and coupling and that the interchangeable parts thereof are within a coupling 80 which is accessible and easy to interchange. Thus as soon as cleaning compound of a paste form is emptied from the magazine the brush can be altered for use with a cleaning powder with a minimum amount of difficulty. If desired, a clip can be supplied to hold this fountain brush in the pocket as it is being carried and many modifications as to structure might be followed without departing 85 from the spirit of the invention or scope 90 of the appended claims.

Having thus described the invention, what is claimed as new and desired to be secured by Letters Patent is:

1. In a fountain tooth brush, a magazine; 95 a brushhead; a removable coupling between the magazine and head; a rotatable rod extending longitudinally of said magazine; a plurality of grooves along the inner face of said magazine; a removable bearing plate 100 for said rod; and lugs integral with said plate and extending into said grooves whereby to prevent rotation of the plate within said magazine, said coupling being positioned against the bearing plate to prevent longitudinal displacement, and to maintain the plate lugs against one end of said 105 grooves.

2. In a fountain brush of the character described, a hollow, tubular, internally 110 threaded magazine, an externally threaded coupling engaging some of said screwthreads; a brushhead in communication with said magazine through said coupling; and a screwthreaded piston movable along the remainder of said magazine screwthreads toward and from said coupling. 115

In testimony whereof, I hereunto affix my signature.
